UNITED STATES PATENT OFFICE.

SAMUEL R. BAILEY, OF AMESBURY, MASSACHUSETTS.

SPRING CONNECTION FOR VEHICLES.

SPECIFICATION forming part of Letters Patent No. 499,086, dated June 6, 1893.

Application filed February 18, 1893. Serial No. 462,824. (No model.)

To all whom it may concern:

Be it known that I, SAMUEL R. BAILEY, of Amesbury, in the county of Essex and State of Massachusetts, have invented a new and 5 useful Improvement in Spring Connections, which will, in connection with the accompanying drawings, be hereinafter fully described, and specifically defined in the appended claims.

10 In said drawings Figure 1, is a transverse section through the side spring and shackle, showing a modification of my method of attaching the end springs of a side-bar buggy to the side-bar, the end spring being shown 15 in elevation. Fig. 2, is a side elevation of the parts shown in Fig. 1, but with the side bar omitted. Fig. 3, is a top plan view of my improved shackle, by which the end spring is connected to the side bar. Fig. 4, is a side 20 elevation of the end of the cross spring, as prepared to be connected with the shackle shown in Fig. 3. Fig. 5, is a section through the spring and coacting parts by which it is 25 connected with the side bar which is shown in transverse section. Fig. 6, is a central longitudinal section through the shackle shown in Fig. 3.

The object of my invention is to provide an 30 improved method by which the end springs of side bar carriages are connected with such side bars; and it consists in turning the extreme ends of the spring upward to a practically vertical position and so connecting the ends of the spring with the shackle that the 35 spring bears against the shackle, while the pin that holds the two parts in place is loosely fitted in the spring.

In Figs. 1, 2, 4 and 5, the end *i* of the spring is shown as upturned at its ends and as entering the socket *n* in which the spring end is 40 loosely secured by pin *p* that passes through the walls of socket *n* and spring *i*. This socket is so formed that the portion in which the spring end is secured enters a recess cut 45 in bar *q*, and it is also formed with ears by which it is clipped to said bar; and it also extends inward and receives the screw *f* that is inserted in said bar. The spring *i* is of full width where it enters said socket, there being 50 no occasion for adding to or diminishing it; it is rounded at the top end to give the spring an easy motion thereon; and although it fits loosely in the socket, yet it will not rattle, for

the reason that the upward motion of the spring is always quicker than that of the load 55 the spring bar *q* carries, or than said spring bar, and hence whether the spring rises or falls it always bears against the socket and and hence cannot rattle.

In Figs. 3, 4, 5 and 6, a somewhat different 6c but closely related method of uniting the spring and side bar is shown, which possesses advantages over that already described, the spring *i* being formed at its upper end with a central rounded and recessed bearing 65 14, between the rounded away ears 15, while the bar plate *n* is formed with a central support 17 with an opening 16 on each side for ears 15 of the spring which fits loosely therein, while part 14 bears against said part 17. 70 The pin *p* passes loosely through the hole 20 in the spring and its flattened ends drop into a cavity in plate *n* under nuts 19 of clip 13; while a yielding packing 21, fitted beneath said pin, prevents its rattling in plate *n*. 75

I am well aware that numerous devices have been patented, which have for their object a connection between the cross spring and side bar, as also between cross springs and side springs; and I claim nothing that is shown or described therein, so far as I at present know, my invention consisting of a spring upturned vertically at the end, and a coupling having a socket recessed into the bar and the end of the spring fitting loosely in said socket and 85 secured by a pin that fits loosely in the spring, the spring and coupling being prevented from rattling by the constant contact and pressure between them.

I claim as my invention— 9c

1. As a connection between spring *i* and spring bar *q*, the cap or plate *n* formed with ears for the clip 13, and with part 17 to be fitted into bar *q*, and the spring *i* upturned at the end and secured loosely in said cap, 95 and formed for said cap to rock upon it, substantially as specified.

2. The combination of part *n* having a raised part 17, fitted in bar *q*, and spring *i* upturned at its end and formed with seat 14, ears 15 100 and hole 20 for pin *p*, substantially as specified.

SAMUEL R. BAILEY.
